Primary Examiner — Karen E Kearney*Assistant Examiner* — Christian P McLean(74) *Attorney, Agent, or Firm* — NSIP Law(57) **CLAIM**

I claim the ornamental design for a display screen or portion thereof with icon, as shown and described.

DESCRIPTION

The sole FIGURE is a front view of a display screen or portion thereof with icon showing my new design.

The dot dash lines in the FIGURE represent the bounds of the claimed design and the portion of the display screen, and form no part of the claimed design.
